JOHN E. BRANTLY, OF BIRMINGHAM, ALABAMA, ASSIGNOR TO DRILLING AND EXPLORATION COMPANY, INC., OF DOVER, DELAWARE, A CORPORATION OF DELAWARE

DRILL CONTROL SYSTEM

Application filed January 5, 1929. Serial No. 330,508.

My invention relates to a method of and apparatus for feed control, and more particularly to a hydraulic feed control for rotary drilling or boring apparatus, such as utilized in drilling oil, gas or water wells in the earth.

In accordance with my invention, a control is effected in response to increase beyond a predetermined value in pressure on the drilling bit, independently of the torque on the drill pipe, whereby descent of the drill is halted until the pressure on the bit has decreased to within its normal range; and further, the rate of feed of the drill is continuous during normal pressure on the bit and is independent of the torque on or exerted by the drill pipe.

Further in accordance with my invention, the weight of the drill shaft or pipe to which bit or boring tool is secured is borne partially by feed control apparatus for regulating the rate of descent of the drill, and the aforesaid feed control apparatus apportions, for a given length of drill pipe, the weight of the pipe between the control apparatus and the bit resting on the bottom of the bore.

Further in accordance with my invention, the feed control apparatus comprises one or more hydraulic cylinders having inlet and discharge valves controlling the substantially non-compressible motive or control fluid, in which a piston or pistons operatively associated with the drill pipe is or are adapted to reciprocate; and more particularly, the discharge valves communicate with a valve for regulating the rate of discharge of fluid from the cylinder or cylinders and with a second valve in series therewith for regulating the pressure at which discharge of fluid from the cylinder or cylinders will take place.

Further and more particularly in accordance with my invention, the entire weight of the drill pipe is adapted to be connected, through suitable mechanism, to the aforesaid piston or pistons which operate as a hydraulic governor or brake against the weight of said drill pipe, automatically to support a predetermined part of the weight of said drill pipe, the remaining weight resting on the drill bit in the bottom of the bore, in accordance with the pressure at which the pres-

sure discharge valve permits flow of fluid from the hydraulic cylinder or cylinders.

Still further in accordance with my invention, the rate of descent of the boring apparatus is independently determined by the extent of opening of the valve controlling rate of discharge from the hydraulic cylinder or cylinders.

My invention further resides in apparatus of the character hereinafter described and claimed.

For an illustration of one of the forms my invention may take, reference is had to the accompanying drawings, in which:

Fig. 1 is a plan view of feed control and operating mechanism for a drill.

Fig. 2 is an elevational view, partly in section, of a hydraulic feed control apparatus.

Fig. 3 is an enlarged detailed view, partly in section, of apparatus shown in Fig. 2.

In boring holes or wells to great depths, as in drilling for petroleum, etc., very serious problems have been encountered due to the great weight of the drill shaft, which generally comprises a string of drill rods, and also to the fact that as the drill descends the rate of drilling will vary to a certain extent, depending upon the varying resistance of the subterranean strata encountered.

In other words, as the drill descends it will tend to drill rather rapidly through soft shales, etc., while its rate will be considerably diminished in drilling through hard rock and equivalent formations. Accordingly, for a fixed drilling rate, the pressure on the bottom of the bore will tend to vary to a considerable extent

in the absence of control apparatus, and in particular will increase to an undesired value when the drill is slowed up, as by hard rock formations, unless the rate of feed is concurrently and correspondingly diminished.

The result of excessive pressure on the bit in the bottom of the bore may cause overloading of the drilling motors, involving possible damage to the drilling equipment, and if the formation through which the drill is passing is soft, may also cause "balling up" of the bit, due to the fact that the excessive drilling rate and pressure for that particular formation prevents the loosened mate-

90
95
100

rial from being properly removed from the bottom of the bore.

Automatic regulation of the rate of boring in accordance with the pressure exerted by the boring tool upon the bottom of the well has previously been attained to a certain extent by differential feed control mechanism, which controls the rate of feed by the differential action between a regulating motor and a drilling or driving motor. The regulating motor runs at substantially constant speed, while the driving motor, if overloaded due to excessive pressure by the boring tool on the bottom of the well, tends to slow up, thereby producing the differential action tending to decrease the rate of drilling, i. e., descent of the drill. The chief disadvantage of this method of feed control is that the drilling pressure must have increased to such value that the consequent overload on the drilling motor causes it to slow up before the control may be effected. In other words, there is a time lag between the occurrence of excessive drilling pressure and the control effected to correct the same which might prove disastrous even to the point of "twisting off" the drill pipe before the excessive pressure was relieved.

It follows, therefore, that the distinctive feature of the differential control method outlined above is that the control is effected only in an indirect sense by the pressure upon the drilling bit. In other words, the control is effected substantially by the increased torque on the drill pipe. This, in itself, is an undesirable feature since it is often necessary to maintain a uniform rate of feed notwithstanding a substantial increase in torque on the drill pipe. For example, in drilling through tough clays or "gumbo" it is desirable that a uniform rate of drilling be maintained, but since the torque on the drill pipe is increased substantially while drilling through this material, it is apparent that control apparatus of the differential type would slow up the drilling considerably.

Another method of feed control utilizes hydraulic means for lowering the drill pipe in short steps at a predetermined rate. The disadvantages of this method are at once apparent, since the operation is neither continuous nor does it automatically control the pressure on the drilling bit. Furthermore, the drilling necessarily progresses at a slower rate due to the fact that a new adjustment of the hydraulic feed control with respect to the drill pipe must be made for each step of its descent.

My invention comprehends apparatus for maintaining the pressure on the bit substantially constant at all times, independently of the torque on the drill pipe and to this end a certain part of the weight of the drill pipe is borne directly or indirectly by the feed control apparatus in accordance with a predeter-

mined adjustment of a fluid pressure regulating valve. That is, by the control apparatus automatically assuming its predetermined share of the weight of the entire drill pipe, the remaining weight, being constant, is borne by the bit and serves to provide the required drilling pressure. Accordingly, when the pressure upon the bit exceeds its normal value, it follows that the feed control apparatus is not supporting its share of the weight of the drill pipe. In response to this decrease in weight upon the control apparatus, further descent of the drill is halted until the control apparatus again picks up its normal share of the drill pipe weight.

It is clear therefore, that as long as the weight on the bit does not exceed a predetermined amount, the drilling will proceed at a substantially uniform rate regardless of the variations in torque on the drill pipe.

Referring to Fig. 1, a source of power M, comprising a driving motor of any suitable type, as electric, gas or steam, is suitably mounted upon base structure 1 and is adapted to be energized from a source of supply (not shown). Motor M comprises a shaft 2 having mounted thereon a sprocket wheel or gear 3 connected to a companion sprocket wheel 4 by the sprocket chain 5. Wheel 4 is keyed or otherwise suitably secured to a line shaft 6 having supporting bearings 7, 8 and 9. A sprocket wheel or gear 10 is freely mounted upon shaft 6 and is in positive connection with a sprocket wheel 11 secured to a shaft 12 through the sprocket chain 13. The shaft 12 is rotatably mounted within bearings 14 and 15, and has mounted thereon a pinion (not shown) for engaging a cooperating ring gear (not shown) for effecting rotation of the rotary table 16. The construction of rotary tables being well known, it is only necessary to state that it engages the drill pipe (not shown) extending centrally thereof to effect rotation of the same for drilling purposes. Operative connection between line shaft 6 and wheel 10 is effected by throwing a clutch 17, which cooperates with shaft 6, into engagement with a cooperating member 17a mounted on the hub of wheel 10. Clutch 17, together with its co-operating member, may comprise what is known as a clutch quill unit, and when closed, as illustrated, affords a direction driving connection between motor M and rotary table 16. Or clutch unit 17-17a may comprise any suitable type of jaw or friction clutch.

A drum shaft 18 is rotatably mounted within bearings 19 and 20, and has mounted thereon a drum 21 comprising a spool-like member upon which a cable (not shown) for supporting the drill pipe may be wound. Drum 21 is fixed with respect to shaft 18, and is operatively connected to line shaft 6 through either sprocket wheel 22 or 23. Sprocket wheel 22 is adapted to rotate with

shaft 18 upon closure of clutch 24, clutch 24 being of the type previously described, and is connected to a companion sprocket wheel 25 secured to line shaft 6 by the sprocket chain 26. In the same manner, sprocket wheel 23, being of smaller diameter, is comparatively connected to shaft 18 through clutch 27, and is connected through sprocket chain 28 to the sprocket wheel 29 secured to shaft 6. Accordingly, by closing either clutch 24 or 27, which in the present instance are shown in open position, it is possible to rotate drum 21 at two different speeds by a motor M to raise or lower the drill pipe.

15 Drum shaft 18 has also mounted thereon a sprocket wheel 30 adapted to rotate with shaft 18 through clutch mechanism 31, shown as closed in the present instance. Wheel 30 is connected to a companion sprocket wheel 32 by a sprocket chain 33 for a purpose hereinafter described.

20 Feed control apparatus for regulating the rate of rotation of drum 21, and consequently the descent of the drill pipe, comprises a base member 34 upon which hydraulic governors 35 and 36 are mounted. A crank shaft 37 mounted within bearings 38 and 39 carried by the base 34 cooperates with connecting rods 40 to effect reciprocation of the same upon rotation of the crank shaft.

25 The above described apparatus may be associated with a derrick, or equivalent structure, in a manner well known in the art.

30 Referring now more particularly to Fig. 2, wherein feed control apparatus comprising a single hydraulic governor or brake 35 is shown, connecting rod 40 is secured in a well-known manner to a cross-head 41 adapted for reciprocation within a cross-head guide 42.

35 Secured to the opposite side of cross-head 41 is a piston rod 42 having mounted thereon piston 43. Piston 43 is adapted to reciprocate within a cylinder 44 having end-plates 45 and 46 suitably secured thereto, the end plate 46 having a bore centrally thereof in registry with a packing gland 47 for receiving piston rod 42. Piston 43 may be of any suitable construction, and in the present instance comprises a plurality of plates 43a, to the periphery of which is secured an annular member 48 of suitable material serving to provide a snug fit between the piston and cooperating cylinder walls. Piston 43 is maintained in position on rod 42 by clamping nuts 49 threaded to rod 42 and engaging piston 43 on opposite sides thereof.

40 Cylinder 44 is provided with inlet passages 50 and 51 at opposite ends thereof, said passages adapted to communicate through valve structure, hereinafter described, with a reservoir 52 containing a substantially non-compressible fluid, as water, for example.

45 Reservoir 52 communicates through pipe 53 with the interior of valve housing 54 having mounted therein a pair of intake valves 55

and 56 adapted to move in unison through a common actuating member 57. Valves 55 and 56 may be of any suitable type, and in the present instance comprise tapered plug members, having their seating surfaces facing each other, mounted upon a common valve stem 58, which is guided for reciprocal motion within the end guides 59 comprising a part of the end closure members or plugs 60, which also serve to provide access to the valve structure. Valve housing 54 is provided with conical valve seats 55a and 56a for cooperating with valves 55 and 56 respectively, and comprises an inlet passage 54a for admitting fluid past valves 55 and 56 to the inlet passages 50 and 51. Accordingly, fluid from the supply conduit 53, which is admitted to passage 54a between valves 55 and 56, may flow by gravity into cylinder 44 through either passage 50 and 51, depending upon the position of valves 55 and 56. The common valve actuator 57 extends through a side of an enlarged portion 61 of the valve housing, and comprises an offset portion 57a, the end of which is secured in any suitable manner to 90 valve stem 58 as by the clamping nuts 57b. The opposite end of actuator 57 is supported and guided by bearing 62 mounted upon the end of a comparatively rigid rod 63 secured to the cross-head guide 42. A rod 65 secured to cross-head 41 is free to move laterally within slot 64 formed in the upper wall of the cross-head guide, during reciprocation of the cross-head, and has mounted at its upper end a housing member 66 comprising a combined valve actuator and buffer. Housing 66 cooperates with stop members 69 and 70 secured to valve actuator 57 for the purpose of seating valves 55 and 56 in accordance with movement of cross-head 41.

45 Referring to Fig. 3, housing 66 comprises a pair of recesses 71 and 72 separated by a wall 73 through which the actuator 57 freely and longitudinally extends. Springs 67 and 68 each seat upon wall 73 and exert compressive forces upon a pair of disc-like members 74 and 75 restrained within recesses 71 and 72 respectively by the inwardly extending annular shoulders 76 and 77. Accordingly, the springs tend to normally maintain discs 74 and 75 in abutting relation to their respective limiting shoulders. Stop members 69 and 70 are provided with reduced portions or members 69a and 70a which are adapted to engage the resiliently biased discs 75 and 74 upon reciprocation of the cross-head to effect reciprocal action of valves 55 and 56. Accordingly, shock to the valve actuator 57 is obviated due to the buffer effect of springs 67 and 68.

50 Cylinder 44 is also provided at its opposite ends with a pair of discharge passages 78 and 79, each adapted to communicate through normally closed discharge valves 80 and 81 to valve structure 82 adapted to regulate the

rate of discharge of the fluid from cylinder 44. Discharge valves 80 and 81 are mounted within housings 83 and 84 connected in any suitable manner, as by conduits, with the discharge passages 78 and 79, and comprise conical valve seats 80a and 81a for cooperating with the correspondingly shaped valves which are normally biased by spring means 80b and 81b to closed position. Valve housings 83 and 84 communicate through connections 85 and 86 to the interior of valve housing 82, having mounted therein a rate of discharge regulating valve 87. Valve 87 is adapted to co-act with conical seat 87a through a threaded valve stem 88 having an adjusting knob 89 secured to its upper end. Rotation of the adjusting knob 89 in either direction effects longitudinal movement of valve 87 with respect to its seat 87a, and accordingly the valve opening may be adjusted to any desired position, depending upon the rate at which fluid is to be discharged from cylinder 44. The valve controlled opening within housing 82 communicates through a pipe connection 90 to a second valve structure 91 adapted to permit flow of fluid therethrough only in response to a predetermined pressure. Disposed intermediate the aforesaid valve structures, and connected to pipe 90, is a pressure gauge 92 for determining the extent of adjustment of the pressure actuated valve.

Valve structure 91 comprises a housing 93 which may be cylindrical in shape, having its lower end closed by a plug member 94 serving both as a valve seat and a connection for pipe 90. A valve 95 is adapted to seat within a correspondingly shaped valve seat in member 94 and is normally biased to seating position by a spring 96 or equivalent, one end of which bears against valve 95 and the other end of which bears against an adjustable abutment 97 whose position along the longitudinal axis of housing 93 may be determined by the adjusting member 98. That is, rotation of member 98 effects longitudinal movement of abutment 97 with respect to valve 95 so as to either increase or relieve the tension on spring 96 so that valve 95 will open only when the predetermined spring tension is overcome. The interior of housing 93 communicates at a point above valve 95 with reservoir 52 through the pipe or conduit 99, thereupon completing a closed system of circulation from and to reservoir 52.

The operation is as follows:

Assuming the apparatus to be in the positions illustrated in Fig. 1, the drill pipe is lowered into the well to a point just above the bottom of the bore and is held in such position by a brake (not shown) cooperating with drum 21. The driving or drilling motor M meanwhile is rotating the drill pipe through the rotary table 16, since clutch 17 is closed to effect rotation of sprocket wheel

10 with the line shaft. With clutch 31 closed as shown, the entire weight of the drill pipe is adapted to be supported through drum 21, drum shaft 18, sprocket wheel 30, chain 33, sprocket wheel 32 and crankshaft 37 to one or more of the hydraulic governors of the feed control apparatus. Since the entire weight of the drill pipe may be readily calculated from known data, it is possible to adjust the tension of the pressure discharge valve spring 96 so that the pressure upon valve 95, which is proportional to the weight of the drill pipe, is not sufficient to lift the valve from its seat. The discharge regulating valve 87 engages its seat 87a to close the discharge passages leading from cylinder 44. Accordingly, piston 43, acting against a substantially non-compressible fluid, is maintained motionless, since escape of fluid from cylinder 44 is prevented, and the weight of the entire drill pipe is carried by the controlling or governing apparatus, or more properly by the derrick associated therewith. Valve 87 is now opened to the desired extent for regulating the rate of flow of fluid from cylinder 44, so that the entire weight of the drill pipe is now representative of the reading of pressure gauge 92. The tension of valve spring 96 is now relieved by member 98 permitting passage of fluid past the valve until the pressure gauge 92 indicates a value representative of the desired proportion of the weight of the drill pipe which is to be supported by the control apparatus. This weight of the drill pipe, transmitted to piston 43 through crankshaft 37 in the manner above described, tends to effect reciprocation of the same to force or pump the non-compressible fluid through the outlet passages and past valves 87 and 95. Assuming now that the weight of the drill pipe tends to rotate sprocket wheel 32 in a clockwise direction, piston 43 will tend to move toward the right in cylinder 44, thereupon forcing the fluid between the piston and end wall 46 through outlet passage 79, past discharge valve 81 which readily opens to permit passage of the fluid, through connection 86, past valve 87 to the pressure regulating valve 95. As piston 43 moves toward the right, the crosshead 41 moving in the same direction, moves the member 66 with respect to the valve actuator 57, but does not effect movement of the same until the piston is near the end of its structure, at which time portion 70a of the stop member 70 is engaged by the spring biased disc 75 to move actuator 57 a short distance towards the right. Valve 56, which during the above described movement of piston 43 was in closed position to prevent escape of the fluid through the inlet passage, now moves to open position, piston 43 being at the limiting position of its stroke, and valve 55 which was formerly opened to permit passage of fluid from reservoir 52, into

the left side of the cylinder as the piston progressed toward the right, is now in closed position, so that upon reversal of movement of piston 43 exhaust of fluid from the cylinder may take place only through the discharge passage 78, etc. With the inlet valves in the position above described, i. e., valve 55 closed and valve 56 open, movement of piston 43 towards the left forces the fluid by way of discharge passage 78 past valves 87 and 95. During the greater part of this movement, member 66 is freely moving towards the left with respect to actuator 57 and does not come into engagement with stop member 69 until it has approximately reached the position illustrated in Fig. 2, at which time actuator 57 is moved to close valve 56 and open valve 55 to permit reciprocation of the piston in the opposite direction. Passage of fluid to cylinder 44 through the inlet valves into the space behind the piston is aided by the suction created by piston 43 in that part of the cylinder.

As long as the weight of the drill pipe tending to rotate sprocket wheel 32 in a clockwise direction, is maintained at a predetermined value, the piston 43 will continue to reciprocate in the manner of a pump acting against a high resistance, and a continuous circulation of the working fluid is maintained through valves 87 and 95. In other words, the hydraulic control apparatus by analogy may be likened to a heavy load which may be moved only upon application of a predetermined force. If the force falls below this value, the load remains stationary, and remains so until sufficient force is again applied.

Since the rate of descent of the drill is effected solely by a portion of its own weight acting upon the piston 43, and also by the adjustment of valve 87, it may happen that this rate of feed will be too rapid for certain rock formations encountered. In this event, the descent of the drill pipe throughout its upper section would be more rapid than the movement of the bit through the more resistant formation, with the result that the bit would be crowded by the greatly increased weight of the drill pipes bearing thereon. Simultaneous with increase in pressure upon the bit, a decrease in weight on the control apparatus occurs, with the result that valve 95 closes due to the decreased pressure thereon, and prevents reciprocation of piston 43. Accordingly, descent of the drill is halted until the bit has drilled sufficiently into the formation to permit the control apparatus to again assume its apportioned share of the weight of the drill pipe, after which the normal drilling rate is resumed. If continuous resistance to such formations is encountered, the discharge valve 87 may be adjusted to further restrict the outlet passage, thereby establishing a slower rate of descent of the

drill in accordance with the higher resistance caused by the more restricted discharge passage. It will of course be apparent that the length of drill pipe cannot be increased indefinitely as the drilling progresses for a given setting of the pressure discharge valve, since the bit pressure would increase to abnormal values. By way of example however, it has been found that for a normal bit pressure of about four tons, about one thousand pounds of drill pipe may be added before changing the setting of the pressure discharge valve.

It will be apparent that weight of the drill pipe carried by the bit, and the rate of drill feed are not necessarily interdependent as in the case of the differential feed control above referred to. That is, for a given setting of the pressure regulating valve 95, which arbitrarily apportions the weight of the drill pipe to be borne by the bit and control apparatus, there may be different adjustments of valve 87 for permitting different rates of feed or descent of the drill. In the same manner, valve 87 may be adjusted for a given rate of feed, and the pressure regulating valve 95 may be tensioned to permit different amounts of the weight of the drill pipe to be borne by the bit. It is therefore within the control of the operator in charge of the drilling operation to independently adjust the rate of feed of the drill as well as the pressure which the bit exerts upon the bottom of the bore.

A further important consideration is that the power required to effect the control is supplied entirely by a portion of the weight of the drill pipe. In other words, no auxiliary motors or other power equipment are necessary to effect the control, as contrasted with the differential method wherein a regulating motor is additionally required.

By my invention, it is possible to prevent damage to the drill pipe, as by "twist-off", by determining in advance substantially the exact pressure brought to bear upon the bit. When this pressure is exceeded, the hydraulic feed control immediately stops further descent of the drill pipe, thereupon permitting the same to rotate within the bore until the bit has entirely cleared itself, and is again operating at its normal pressure. Furthermore, since from past experience it is possible to roughly estimate the proper drilling rate through different rock formations, a given rate of feed may accordingly be established by regulation of the discharge valve, the pressure valve being also adjusted to provide adequate working pressure on the bit, so that more "footage" of well, i. e. higher average rate of feed, is obtained than by any of the methods previously referred to. In large scale drilling operations, loss of time is very costly and the comparatively

70

130

high average rate of drilling effected by my method and apparatus therefore has a distinct commercial advantage.

From the viewpoint of operation, my invention has still further advantages in that the driller has only to set the valves for the proper rate of feed and bit pressure, after which the apparatus is substantially self-operating within the limits previously mentioned. No close and constant supervision is required as in the case of the differential method where the operator should be on hand to de-energize the drilling motor in case of sudden overload thereon, in order that the drill pipe may not "twist off", or as in the case of the step-by-step method of feed which requires constant attendance and supervision.

Although I have described the operation of but one hydraulic control cylinder for regulating the rate of descent of the drill, and the extent of pressure exerted by the bit on the bottom of the bore, it shall be understood that two or more hydraulic control cylinders of the same type may be readily employed if desired, depending of course on the operating requirements. In such an event, the different pistons are operatively connected to a crank-shaft in the manner illustrated in Fig. 1, and the discharge passages of each cylinder connected to valves 87 and 95, which valves are common to the multiple cylinder arrangement and independently regulate the rate of flow of fluid from the cylinders and the pressure at which fluid may be discharged therefrom. The operation of the pistons in the multiple cylinder arrangement may be either synchronous, as where the connecting rods are connected to the same throw of the crankshaft, or in timed sequence, as in the operation of internal combustion engines, for example, although the latter arrangement is preferred.

It shall be further understood that my invention is not limited to the specific structure herein described, but comprehends in general a hydraulic governor or governors wherein substantially continuous though alternate, movement of a member is resisted by a non-compressible fluid, the release of said fluid being subject to a variable resistance.

It shall still further be understood that the term "drill pipe" as used in the above specification and appended claims is intended to comprehend means for transmitting rotative movement from the drill actuating means to the bit, including both drill rod and pipe.

What I claim is:

1. In brake apparatus for restraining movement of a load under the action of gravity, a hydraulic cylinder having inlet and discharge passages at opposite ends thereof, a piston adapted for reciprocal movement within said cylinder, means providing for connection of the load to the piston to effect reciprocation thereof, valve structure asso-

ciated with said discharge passages for permitting escape of fluid from said cylinder only in response to predetermined force exerted thereon by said piston, valve structure associated with said inlet passages, and operative connections with said piston for actuating said last-named valve structure.

2. In brake apparatus for restraining movement of a load under the action of gravity, a cylinder, a piston operable in said cylinder, a source of liquid supply, valve means movable to different positions and operable when in either position to establish communication between said supply and the cylinder on one side of said piston and to cut off communication between said supply and the cylinder on the other side of said piston, means movable with said piston and operable substantially upon completion of the piston stroke in either direction to reverse the position of said valve means, a discharge connection, check valves biased to closed position and providing respectively for liquid discharge into said connection from opposite ends of said cylinder, each of said check valves disposed to open with the pressure in said cylinder, valve means disposed in said discharge connection and operable when closed to oppose liquid flow therein, and means yieldingly holding said last-named valve means in closed position.

3. A braking system for controlling the descent of a load comprising a cylinder adapted to receive a substantially non-compressible fluid, a piston reciprocated in said cylinder by descent of said load, valve structure in the path of fluid discharged from said cylinder adjustable to predetermine the maximum rate of descent of said load, and pressure responsive valve structure in said path preventing discharge from said cylinder and descent of said load when said load is less than a predetermined magnitude.

4. A braking system for controlling the descent of a load comprising a cylinder adapted to receive a substantially non-compressible fluid and having inlet and discharge passages at opposite ends thereof, a piston reciprocated in said cylinder by descent of said load, valve structure in the path of discharge of fluid from said cylinder which closes to prevent movement of said piston when the force exerted thereon by said load is less than a predetermined minimum, valves controlling admission of fluid to said cylinder through said inlet passages, and structure movable in timed relation to said piston for actuating said inlet valves substantially at the end of the piston stroke to open the valve at the end of the cylinder adjacent the piston and to close the inlet valve at the opposite end of the cylinder.

5. A braking system for controlling the rate of descent of a rotary drill comprising a cylinder adapted to receive a substantially

non-compressible fluid, a piston reciprocated in said cylinder by descent of said drill, valve structure in the path of fluid discharged from said cylinder adjustable to predetermine the maximum rate of descent of said drill, and pressure-responsive valve structure in said path preventing discharge from said cylinder and descent of the drill when the force exerted by said drill on said piston is less than a predetermined minimum.

6. A braking system for controlling the pressure at the cutting end of rotary drill apparatus comprising a cylinder adapted to receive a substantially non-compressible fluid, a piston reciprocated in said cylinder by descent of said drill, a valve in the path of fluid discharged from said cylinder and responsive to the pressure thereof for closing said path to stop descent of the drill when said pressure exceeds a predetermined maximum, and a second valve in said path to control the rate of descent of said drill independently of said pressure.

7. A braking system for controlling the descent of a load comprising a cylinder adapted to receive a substantially non-compressible fluid, a piston reciprocable in said cylinder to act on fluid therein for both directions of movement, means connecting said piston to said load for effecting reciprocation thereof upon descent of the load, and valve structure adjustable to permit discharge of fluid from said cylinder at a desired rate to effect continuous descent of the load at a constant and desired rate.

JOHN E. BRANTLY.
